WEB SEVERING AND TRANSFER DEVICE

Joseph A. Doyle, New Dorp, and Edward Hutchins,
Corinth, N. Y.; said Hutchins assignor to
International Paper Company, a corporation of
New York

Application July 29, 1942, Serial No. 452,692

14 Claims. (Cl. 242—56)

The present invention relates to a web severing and transfer device, and more particularly relates to such a device for use in connection with a continuously moving web which is to be wound upon a plurality of separate reels.

Many forms of machinery are adapted to produce or operate upon a continuous web. Such machinery naturally will discharge the web in a continuous operation. In order that the web may be wound in practicable quantities upon separate reels it is necessary to discontinue the winding upon a reel which has received its predetermined quantity and to initiate winding upon an empty reel without stopping the continuous operation of the web producing or treating machine. For example, in the paper industry a papermaking machine produces a continuous web of paper and under ideal circumstances the machine may not be shut down for several days. Similarly, paper coating machines are most efficiently run in a continuous manner, and to this end paper may be supplied to them from a succession of reels which are so handled as to splice the leading end of a new reel to the trailing end of a spent reel. These splices may be made by any of the well-known flying splice mechanisms and unless it is necessary to stop the machine for the purpose of changing the rewinding reels, the coating operation may be continuously performed. In either of these examples as well as in many other instances it is highly desirable to provide for instantaneous transfer of the web from one rewinding reel to another.

Various reeling devices are known which are capable of handling a continuously moving web. One widely used form is that shown in U. S. Patent No. 1,248,542, granted December 4, 1917, to C. E. Pope, and this particular reeling device is known throughout the paper industry as the "Pope reel." The present invention is particularly adapted for use in conjunction with the Pope reel although obviously it is not limited in its use to such a reel. For the purposes of description the invention will be set forth in connection with the Pope reel.

In general the Pope reel comprises a driving drum which is rotated at a peripheral speed equal to the speed of movement of the web with which it is to be used. Empty reels are placed into frictional contact with the surface of the driving drum and the leading end of the paper is secured in some manner to the empty reel whereby rotation of the driving drum will serve to rotate the empty reel and wind the paper therearound. When a predetermined quantity of paper has been

wound upon the reel it is necessary to shift the filled reel while it continues to wind to a position permitting the insertion of a new empty reel. Normally the web is brought up over the upper peripheral portion of the driving drum and an empty reel is lowered into frictional contact with the upper surface of the web upon the drum. Assuming that the papermaking or other web handling machine has just been started, a certain quantity of the web is permitted to go beyond the empty reel until such time as conditions in the machine have become sufficiently uniform to make it advisable to begin the reeling operation. At this time the web is severed along a line just beyond the empty reel and the leading edge thus formed is directed upwardly around the empty reel. The directing of the web may be accomplished by the use of jets of air or water or steam, or may be accomplished by some mechanical manipulation or even by manual manipulation. Assuming a manual manipulation, the leading edge is gripped by operators at opposite sides of the machine and is thrown up and over the empty reel whereby the leading edge drops down upon the upper face of the web progressing toward the reel. This serves to drag the leading edge into the nip between the winding reel and the driving drum and forms a bight having sufficient friction to secure the web to the winding reel. From this point on the web will be progressively wound upon the reel.

At an appropriate time the partially wound reel may be moved along the periphery of the driving drum in the direction of rotation thereof and brought to rest in a suitable bearing mechanism wherein it continues to wind in order to accumulate the predetermined quantity of web material. In the meantime a new empty reel is brought into position and is suspended just above the driving drum in a position ahead of the reel upon which the web is being wound. When the predetermined quantity is reached it is necessary to sever the web at a point between the empty reel and the filled reel and it is necessary to direct the leading edge of the web around the empty reel to initiate winding upon the same.

With many grades of paper the various forms of manipulation mentioned above are satisfactory. However, when an extremely heavy web, as for example a paper board, is being handled or produced by the machine the ordinary systems of transferring the leading edge to the new reel are ineffective. Many expedients have been resorted to, but in many instances it has been found to be necessary to stop the machine each time a wind-

ing reel is changed. In the case of a coating machine the whole machine may be stopped, and certain portions of the web will necessarily be improperly coated and/or dried. In the case of a papermaking machine, the problem of stopping the machine is so great that the normal procedure is to sever the web somewhere ahead of the winding station and to permit the web to be wasted during the time necessary to effect the change. Obviously, either of these expedients results in an increase in mill costs.

Accordingly, it is an object of this invention to provide means for effecting the transfer of a web from one reel to another completely automatically.

It is a further object of this invention to provide means for binding first the edge portions of a web to a rotating reel and progressively binding portions of the web extending toward the center thereof to the reel while a progressively diminishing central portion of the web continues to proceed beyond the reel.

It is a further object of this invention to provide means of the type stated which will operate without the necessity for special manipulation of any type.

It is a further object of this invention to provide a winding reel with means for securing a web thereto which becomes automatically operated upon initiation of rotation of said reel.

It is a further object of this invention to provide a winding reel with a loop of wire or other flexible elongated material secured at its opposite ends to the opposite ends of the reel for the purpose of securing a web thereto.

It is a further object of this invention to provide in a machine having a winding reel of the type just described a control device for insuring reliable operation of said web-securing means.

It is a further object of this invention to progressively secure an increasing width of a moving web to a winding reel while a proportionately decreasing width of said web continues to be wound upon another winding reel.

It is a further object of the present invention to provide a mechanism in which there is a first reel upon which a continuously moving web is being wound and a second reel upon which it is desired to transfer the web, together with an automatically operated device for severing and securing said web to said second reel.

Other and further objects of this invention will become more apparent upon a reading of the following specification in which is described a preferred, but obviously not necessarily the only, form of embodiment of the invention and by reference to the drawings forming a part of the specification.

In the drawings, wherein similar parts are identified by similar characters of reference throughout the several views

Fig. 1 is a side elevation of a winding and severing device embodying the present invention;

Fig. 2 is a plan view of the device shown in Fig. 1 looking in the direction indicated by the arrow II in Fig. 1, certain parts having been moved from their normal position for the purposes of illustration;

Fig. 3 is a view similar to Fig. 2 illustrating certain steps in the operation of the mechanism;

Fig. 4 is a view similar to Fig. 2 illustrating the condition of a winding reel when the operation of the mechanism is complete;

Fig. 5 is a fragmentary view illustrating the operation of winding a web upon a new reel; and

Figs. 6 and 7 are elevational and sectional views, respectively, of a detailed mechanism.

Referring now to the drawings, there is diagrammatically illustrated in Fig. 1 a drum 10 and a felt 11 guided around a suitable felt roll 12 from which is discharged a continuous web 13 moving in the direction of the arrow 14 around suitable guide rolls 15 and 16. It will be understood that the mechanism thus far described may

comprise the last drying stage of a papermaking machine, in which event the drum 10 is a drier drum and the felt 11 is a portion of the felt normally used for conducting the web through the drying stages. It will be further understood that the mechanism thus shown is purely illustrative and that the web 13 may be discharged from any suitable machine from which it is desirable to discharge a continuous web of paper, fabric and the like. Thus, for example, the web 13 may be discharged from a paper coating machine or paper finishing machine such as a calendar stack, or from a fabric weaving or treating machine.

From the guide roll 16 the web 13 is conducted over the upper peripheral portion of a driving drum 17 which is driven for rotation in the direction of travel of the web and preferably at or substantially at the speed of travel thereof. As shown in the drawings, the driving drum 17 is rotating in a counter-clockwise direction. The web 13 progresses across the drum and is wound upon a reel 18 from which protrudes the ends of a shaft 19 which is rotatably supported in a pair of bearings 20, 21 formed upon the upper ends of arms 22 and 23, respectively, fixed for rotation with a shaft 24 rotatably mounted in bearings 25 secured to the base 26 of the winding device. As the web continues to wind upon the reel 18 it forms a roll of increasing diameter, and as the diameter increases the shaft 19 will be moved progressively away from the periphery of the driving drum 17. The movement of the shaft 19 will be in an arcuate path described by the swinging of the arms 22, 23 within the bearings 25.

The ultimate diameter of the roll wound upon the reel 18 will be predetermined for particular circumstances. When this diameter is reached it is necessary to discontinue further winding upon the reel 18 and to make some other provision for the continued supply of web 13.

The mechanism illustrated in Fig. 1 for handling a continuous supply of web is that commonly known as the "Pope reel." In general the Pope reel is provided with a pair of side frames 27, 28 which are pivoted upon suitable bearings 29 and 30, respectively, supported upon the base 26 in a position eccentric to the drive shaft 31 for the driving drum 17. As shown in the drawings, the bearings 29 and 30 may be formed as a part of the pillow blocks 32 and 33 within which the drive shaft 31 is rotatably received. These pillow blocks are rigidly secured to the base 26.

The side frames 27 and 28 have formed thereon open bearings 34 and 35, respectively, which are provided with elongated slots within which may be rotatably received the shaft of a paper winding reel. The proportions of the open bearings 34 and 35 are such that the shaft of an empty reel may be received therein when the side frames 27 and 28 are in the position illustrated in Fig. 1. The empty reel may be maintained out of contact with the periphery of the driving drum 17 or it may be lowered into contact therewith. When the web has been secured to this empty paper reel and winding thereon begins the di-

ameter thereof will progressively increase and the elongated slots will permit movement of the reel shaft away from the periphery of the driving drum while maintaining accurate control of the shaft.

Thus in Fig. 1 there is illustrated in full lines an empty reel 36 whose shaft 37 is positioned within the bearing slots of the bearings 34, 35. This empty reel will be suspended in the position shown in full lines by suitable overhead crane mechanism indicated generally at 31a, as is well understood in the papermaking art. When the desired diameter has been built up upon the active reel 18 the empty reel 36 is lowered within the bearings 34 and 35 into peripheral contact with the web 13 as it progresses across the upper portion of the drum 17. This will result in rotation of the reel 36 and under normal operation of the Pope reel the web 13 must be severed, permitting the trailing edge thus formed to continue on to the reel 18 while the leading edge thus formed must be conducted around the empty reel 36 to initiate winding thereon.

When this has been accomplished the filled reel 18 is swung away from the driving drum by rotation of the shaft 24 by any suitable mechanism such as the hand wheel 38, and it is then removed from the bearings 20, 21 for such disposal as may be desired. The bearings 20, 21 are then swung back into proximity with the periphery of the driving drum 17 in such a position as to receive the shaft 37 of the new reel 36. In the meantime it will be appreciated that the web has continued to wind upon the reel 36 and that the diameter thereof is progressively increasing. It is desirable at this juncture to move the reel 36 from the bearings 34, 35 to the bearings 20, 21. To this end the side frames 27 and 28 have formed thereon gear segments 39, 40 which are concentric with the bearings 29, 30. The gear segments 39 and 40 mesh with pinions, one of which is shown at 41 in Fig. 1, fixed upon a shaft 42. The shaft 42 is rotatably carried in suitable bearings, one of which is shown at 43 in Fig. 1. The shaft 42 also has fixed thereon a hand wheel 44 by which it may be rotated for the purpose of swinging the side frames 27, 28 about their respective bearings 29, 30.

Rotation of the hand wheel 44 in a clockwise direction will cause a swinging of the frames 27, 28 in a counterclockwise direction whereby to move the reel 36 in the direction of rotation of the driving drum 17, while the web continues to wind thereupon. Inasmuch as the centers of the bearings 29 and 30 are eccentric to the drive shaft 31 of the drum 17 this shifting movement of the reel 36 will tend to move the shaft 37 thereof out of the open bearings 34, 35. The position assumed by the bearings 20, 21 is so related to the path of the bearings 34, 35 and shaft 37 carried therein that the shaft 37 is discharged from the bearings 34, 35 into the bearings 20, 21. Thus the reel 36 will thereafter be supported in the bearings 20, 21 and operations will proceed as above outlined in connection with subsequent empty reels which may be introduced into the bearings 34, 35.

The above description has reviewed in a brief manner the operation of the Pope reel, and such operation is old and well known. The present invention is particularly adapted for use in connection with the Pope reel, and it is for this reason that the above description has been made. It will be appreciated that any desirable variations may be made in the Pope reel mechanism

without affecting the cooperation of the present invention therewith, and it will be further understood that the present invention is equally well adapted, in its present form or in such forms as may be within the scope of the appended claims, for cooperation with other forms of continuous reeling mechanism.

Referring now to Fig. 2, it will be observed that the reel 36 chosen for illustration in connection with the present invention may comprise a core portion 45 which may be made of any suitable material, as, for example, laminated paper, and end caps 46 and 47 which may be formed of metal. These end caps are secured in any suitable manner to the core portion 45 and are preferably keyed to the shaft 37. Each of the caps 46 and 47 has a depression 48 formed therein (see Fig. 5) within which is secured a stud or screw 49 in such position as to lie within the peripheral confines of the cap. It will be understood that the reel 18 is constructed similarly to the reel 36, and it will be further understood that all reels intended for use in conjunction with the present invention will be similarly constructed. The following description will be confined to the reel 36 and it is understood that the operation in conjunction therewith is identical with the operation in conjunction with other similar reels.

After the reel 36 has been lowered into the position illustrated in full lines in Fig. 1, i. e., a position adjacent to but out of contact with the driving drum 17, an elongated flexible member 50, such as a wire, cord, twine or cable, is fastened to the stud 49 secured within the cap 47. For purposes of convenience the member 50 will be hereafter referred to as a wire. The wire 50 is carried downwardly from the reel 36 alongside the web 13 and beneath the web. It is then conducted across the machine and upwardly past the opposite edge of the web 13, and its other end is secured to the stud 49 located within the cap 46. There is thus formed a continuous loop of wire extending from end to end of the reel 36 and including within it the web 13.

So long as the reel 36 does not rotate the wire 50 will remain out of contact with the web 13, and it will not interfere with the continuous movement of the web therethrough as the same is wound upon the reel 18. When it becomes necessary to transfer the web from the reel 18 to the reel 36 the reel 36 will be lowered into peripheral contact with the upper face of the web 13, and the reel will immediately begin to rotate. When such rotation starts the wire 50 will be wound upon the reel 36, and since the wire is in the form of a continuous loop, winding thereof will rapidly progress toward the center of the web. Thus the wire will progressively form helical turns around the reel until such time as the entire loop has been taken up. As this operation begins the wire will be brought into contact with the opposite edges of the web 13 and will cut into these edges. Inasmuch as the wire is progressing toward the center of the machine the portion of the web which is severed thereby will necessarily be encompassed within the turns of wire and will thereby be secured to the reel 36. After a few turns the loop will be entirely taken up and the web will have been severed inwardly toward the center, the central portion thereof having been decreasingly directed to the reel 18 and the outer portions thereof having been increasingly directed to the reel 36.

As thus far described, the wire loop may hang freely from the reel 36, and it may be so dis-

posed as to normally hang out of contact with the web. This arrangement is entirely capable of performing the objects of my invention, but it will be appreciated that the freely hanging wire may in some instances be objectionable. For example, the proximity of this freely hanging wire to a rapidly moving web may lead to inadvertent contact therebetween and damage to the web. Accordingly it has been found desirable to provide some form of means for holding the loop in a predetermined shape and insuring freedom from inadvertent contact with the web. It has also been found desirable to control the winding of the loop upon the reel in such a manner as to relatively evenly space the helical turns across the width of the reel. This latter provision leads to more reliable operation of the device. Accordingly, there is illustrated a form of mechanism for yieldingly holding the loop in a predetermined shape and for symmetrically guiding the loop during the winding thereof upon the reel.

As shown in the drawings with particular reference to Fig. 2, the wire 50 is conducted beneath the web and around a pair of sheaves 52 carried by the free ends of pivoted arms 53 and 54, respectively. At their lower ends the arms 53 and 54 are hinged to a frame member 55, and they have fixed for rotation therewith a pair of wheels 56 and 57, respectively. The wheels 56 and 57 are interconnected by a crossed belt 58 which serves to force equal angular rotation in opposite directions upon the arms 53 and 54. A pair of springs 59 and 60 are respectively tensioned between the arms 53 and 54 and a stationary portion of the frame. The springs 59 and 60 tend to rotate the arms 53 and 54 away from one another and thus to separate the sheaves 52. Due to the interconnection of the arms through the belt 58 the sheaves 52 will be maintained substantially symmetrically on either side of the center of the machine. The loop of wire 50 is thus spread into a generally rectangular shape as illustrated in dot and dash lines in Fig. 2. Upon winding of the loop on the reel 36 the arms 53 and 54 will be drawn toward one another against the tension of the springs 59 and 60 and the wire will thus be held under tension and guided symmetrically toward the center of the web 13.

Suitable mechanism must be provided for releasing the loop in order that it may be permitted to complete its winding upon the reel 36. A preferred form of releasing mechanism is illustrated in the drawings and is shown in detail in Figs. 6 and 7. In these figures the arm 53 and the release mechanism associated therewith are illustrated and it will be understood that an identical release mechanism is provided on the arm 54.

A U-shaped bracket 61 is secured by bolts 62 to the end of the arm 53 in such position that one leg of the U is brought into contact with the arm. The other leg of the U is laterally spaced from the arm by a spacing block 63 through which the bolts 62 pass. The bracket 61 and arm 53 thus define an open channel 64. The web of the bracket 61 extends over the end of the arm 53 and it has formed therein a notch 65 of suitable dimensions to receive a pivoted block 66. The block 66 is pivoted upon a pin 67 passing through the bracket 61 and the end of the arm 53 in a direction transversely of the channel 64. One end of the block 66 is threaded to receive the bearing-stud 68 upon which the sheave 52 is freely rotatable. The

other end of the block 66 extends below the pin 67 for a distance approximately equal to the remaining depth of the channel 64. When the block 66 is rotated into the position shown in full lines in Figs. 6 and 7 the axis of the stud 68 forms a substantial continuation of the arm 53. When the block 66 is rotated into the position shown in dot and dash lines in Figs. 6 and 7 the axis of the stud 68 extends substantially at right angles to the arm 53.

Inasmuch as the axis of the pin 67 is transverse the channel 64 a pull exerted upon the sheave 52 crosswise of the arm 53 will be ineffective to rotate the block 66 about the pin 67. However, a pull substantially lengthwise of the arm 53 will be effective to rock the block 66 about its pin 67 and thus to move the sheave 52 from the position shown in dot and dash lines in Figs. 6 and 7 to the position shown in full lines therein.

Referring now to Fig. 2, it will be observed that the sheaves 52 are arranged in the positions illustrated in dot and dash lines in Figs. 6 and 7. In these positions the wire 50 is guided around the sheaves and it will be appreciated that the pull thus exerted upon the sheaves will be ineffective to move the blocks 66 from their position. When the wire 50 is wound upon the reel 36 and the arms 53 and 54 progressively move through the position shown in full lines in Fig. 2 the pull of the wire gradually shifts from a direction transverse the arms to a direction approaching the longitudinal. When the arms reach the position shown in full lines in Fig. 3 the pull of the wire upon the sheaves has become substantially longitudinal, and the blocks 66 will be caused to rotate as shown in this figure. Thus the sheaves 52 will be moved to a position in which they are incapable of holding the wire. Actual release of the wire has occurred when the arms 53 and 54 reach the position shown in dot and dash lines in Fig. 3.

A suitable abutment 69 may be secured to the frame member 55 for limiting the movement of the arms 53 and 54. It may be desirable to form this abutment of some resilient material such as rubber in order to avoid damage to the parts.

The operation of the device will now be set forth.

Referring to Fig. 1 it will be assumed that the empty reel 36 is suspended adjacent to but above the periphery of the driving drum 17 and that the wire 50 has been secured to the studs 49 whereby to form a loop extending outside the edges of the web 13 and transversely beneath the web over the sheaves 52. The wire 50 will thus be arranged as shown in dot and dash lines in Fig. 2. When it is desired to transfer the web from the reel 18 to the reel 36 it is only necessary to lower the reel 36 into peripheral contact with the upper surface of the moving web 13. Frictional engagement will immediately cause rotation of the reel 36 accompanied by winding of the wire 50 therearound. Winding of the wire will serve to shorten the loop and thus to swing the arms 53 and 54 toward one another. Very shortly after winding commences the wire will be brought into engagement with the opposite edges of the web 13 and will cut into the web along a line rather closely coinciding with the line of contact between the reel 36 and the drum 17. Cutting of the web is actually effected by the action of the wire 50 in binding a portion of the web to the reel 36 and thus the line of severance will lie on the side of the wire toward

the center of the machine. This is illustrated in Fig. 2 wherein a tab 13a has been cut from each of the edges and is bound to the reel 36 by the first turn of the wire 50. As rotation of the reel 36 continues the tabs 13a become progressively wider and are wound upon themselves with the wire interposed, as illustrated in Fig. 3. This operation continues until the wire is released by the shifting of the sheaves 52 on the ends of the arms 53 and 54. The remaining portion of the wire loop will be rapidly wound upon the reel 36 and transfer will be complete.

In each of Figs. 2 and 3 the reel 18 has been moved from its actual position in order that the progress of the web thereto might be illustrated. It will be observed that the trailing end of the web tapers to a relatively narrow width and that the central portion of the web is finally severed substantially straight across, as illustrated at 13b in Fig. 4.

In Fig. 5 there is a further detailed showing of the manner in which the tabs 13a are secured to the reel 36. In this view the overlying portions of the tab have been broken away in order to illustrate the arrangement of the line of severance on the side of the wire 50 toward the center of the machine. The wire 50 is also illustrated as extending from its control mechanism to the nip between the reel 36 and drum 17 from which it proceeds to wind helically about the reel 36. In this view it is thus entirely clear how the wire serves to sever the web and to bind it to the reel 36.

From the above detailed description of a preferred form of this invention it will be apparent that there is provided an apparatus fulfilling the objects of this invention. It will be apparent to those skilled in the art that modifications and variations may be resorted to within the scope of the appended claims.

What is claimed is:

1. In a winding device, the combination of means for continuously moving a web; a reel; an elongated flexible member secured at its opposite ends to the opposite ends of said reel, whereby to form a loop through which said web is continuously moved; and means for initiating rotation of said reel whereby to progressively wind said loop thereupon, said loop being initially brought into contact with the opposite edges of said web and continued rotation of said reel causing said loop to progressively sever said web inwardly toward the center thereof from each of said opposite edges, and said loop progressively securing the severed portions of said web to said reel whereby upon complete winding of said loop upon said reel the full width of said web will be secured to said reel for winding thereupon.

2. In a winding device, the combination of means for continuously moving a web; a reel; means for supporting said reel in a position adjacent one face of said web but out of contact therewith; elongated flexible material secured to the opposite ends of said reel; means for holding said flexible material adjacent the opposite edges of said web but out of contact therewith; means for initiating rotation of said reel whereby to wind said flexible material thereupon, said holding means being so constructed and arranged as to guide said flexible material during winding thereof upon said reel to form helical turns thereof upon said reel extending inwardly from the opposite ends of said reel whereby to sever said web and secure said severed web to said

reel for winding thereupon, said holding means releasing said flexible member when formation of helical turns has progressed substantially to the center of said reel.

3. In a winding device for a continuously moving web, the combination of means for moving said web in a predetermined path of travel; a winding reel, means to support said winding reel adjacent to but out of contact with one face of said web, an elongated flexible member secured at its opposite ends to the opposite ends of said winding reel in such manner as to form a loop extending around the edges of said web and continuously across the opposite face thereof, means to initiate rotation of said winding reel whereby to progressively wind said loop inwardly toward the center of said reel to progressively decrease the size of said loop, said loop being brought into contact with the edges of said web and said opposite face thereof whereby to progressively sever and bind said web to said winding reel.

4. In a winding device for a continuously moving web, the combination of means for moving the web in a predetermined path of travel; a winding reel; means to support said winding reel adjacent to one face of said web; an elongated flexible member secured at its opposite ends to the opposite ends of said reel and extending around the edges and across the opposite surface of said web whereby to form a loop; means for initiating rotation of said winding reel; and releasable means for guiding said loop-forming member from the opposite ends of said winding reel progressively toward the center thereof whereby to form a series of helical turns extending inwardly from the opposite ends of said reel, said loop-forming member thus engaging the edges of said web to sever the same and continuing to sever said web progressively toward the center thereof while engaging said opposite surface of said web to bind said web into winding engagement with said winding reel, said guiding means releasing said loop when winding thereof upon said reel is substantially complete.

5. In a winding device for a continuously moving web, the combination of a first reel, means for winding said web upon said first reel, a second reel, and means for transferring said web from said first reel to said second reel without interrupting the continuous movement thereof, said last-named means comprising a loop of flexible elongated material secured at its opposite ends to the opposite ends of said second reel.

6. In a web-winding device, the combination of means for moving a continuous web to a first winding reel, a second winding reel, means to support said second reel adjacent to the path of said web, an elongated flexible member secured at its opposite ends to the opposite ends of said second reel whereby to form a loop encompassing but out of contact with said web, and means to initiate rotation of said second reel whereby to wind said loop thereupon to sever said web and secure said severed web to said second reel.

7. In a winding device for a continuously moving web, the combination of a first reel, means for winding said web upon said first reel, a second reel, means for transferring said web from said first reel to said second reel without interrupting the continuous movement thereof, said transferring means comprising an elongated flexible member secured at its opposite ends to the opposite ends of said second reel in such manner as to form a loop encompassing said web, and means for initiating rotation of said

second reel whereby to wind said loop thereupon to progressively sever said web and secure said severed web to said second reel while said loop is progressively wound from its opposite ends toward the center of said reel.

8. In a winding device, the combination of means for continuously moving a web, a reel, an elongated flexible member secured at its opposite ends to the opposite ends of said reel whereby to form a loop, releasable means engageable with said loop to hold the same in a position adjacent to but out of contact with said web and encompassing said web, and means for initiating rotation of said reel whereby to progressively wind said loop thereupon, said holding means guiding said loop progressively into contact with said web whereby to sever said web and secure said severed web to said reel.

9. In a winding device the combination of means for continuously moving a web; a reel; means for mounting said reel in a position adjacent to one side of said web and out of contact therewith; an elongated flexible member secured at its opposite ends to the opposite ends of said reel whereby to form a loop; a pair of sheaves located on the opposite side of said web around which said loop is guided; means yieldably urging said sheaves to positions in which they are effective to hold said loop out of contact with and encompassing said web; means for initiating rotation of said reel whereby to progressively wind said loop thereupon; said sheaves being moved, as an incident to the winding of said loop upon said reel, toward one another and toward the center of said web whereby to guide said loop progressively toward the center of said reel; and automatically operable means for disengaging said sheaves from said loop to permit completion of winding thereof upon said reel.

10. In a winding device for a continuously moving web, the combination of a first reel; means for winding said web upon said first reel; a second reel; means to support said second reel adjacent to one face of said web; means for transferring said web from said first reel to said second reel without interrupting the continuous movement thereof, said transferring means comprising an elongated flexible member secured at its opposite ends to the opposite ends of said second reel and extending around the edges and across the opposite surface of said web whereby to form a loop; means for initiating rotation of said second reel and releasable means for guiding said loop-forming member from the opposite ends of said second reel progressively toward the center thereof whereby to form a series of helical turns extending inwardly from the opposite ends of said second reel, said loop-forming member thus engaging the edges of said web to sever the same and continuing to sever said web progressively toward the center thereof while engaging said opposite surface of said web to bind said web into winding engagement with said second reel, said guiding means releasing said loop when winding thereof upon said second reel is substantially complete.

11. In a winding device for a continuously moving web, the combination of a first reel, means for winding said web upon said first reel, a second reel, means for transferring said web from said first reel to said second reel without interrupting the continuous movement thereof, said last named means comprising a flexible elongated member secured at its opposite ends to the opposite ends of said second reel to form a loop,

10 and means for temporarily holding said loop in a position encompassing but out of contact with said web.

12. In a winding device the combination of a rotatable driving drum, means for rotating said

15 drum, means for guiding a web over a portion of the surface of said drum whereby to drive said web, a winding reel, means for supporting said winding reel in a position adjacent to but out of contact with the portion of said drum over which

20 said web is driven, an elongated flexible member secured at its opposite ends to the opposite ends of said reel forming a loop encompassing a portion of said web out of contact with said winding drum, and means for moving said reel into contact with said web upon said winding drum to cause rotation of said reel whereby to wind said loop upon said reel to sever said web and to secure said severed web to said reel.

13. In a winding device the combination of

30 means for continuously moving a web, a reel, fastening means mounted adjacent each end of said reel for rotation therewith in a path encircling the axis of rotation of said reel, an elongated flexible member secured to said fastening

35 means and extending therebetween to form a loop through which said web is continuously moved, and means for rotating said reel when it is desired to wind said web thereupon, the rotation of said reel serving to progressively wind said loop

40 upon said reel whereby to sever said web and secure said severed web to said reel.

14. In a winding device the combination of

means for continuously moving a web, a reel, fastening means mounted adjacent each end of

45 said reel for rotation therewith in a path encircling the axis of rotation of said reel, an elongated flexible member secured to said fastening means and extending therebetween to form a loop through which said web is continuously moved,

50 and means for rotating said reel when it is desired to wind said web thereupon, the rotation of said reel serving to progressively wind said loop upon said reel, said loop being initially brought into contact with the opposite edges of said web,

55 and continued rotation of said reel causing said loop to progressively sever said web inwardly toward the center thereof from each of said opposite edges and said loop progressively securing the severed portions of said web to said reel

60 whereby upon complete winding of said loop upon said reel the full width of said web will be secured to said reel for winding thereupon.

JOSEPH A. DOYLE,
EDWARD HUTCHINS.
